UNITED STATES PATENT OFFICE.

KENNETH HOWIE, OF NORRISTOWN, PENNSYLVANIA, ASSIGNOR, BY MESNE ASSIGNMENTS, TO WILDMAN MFG. CO., OF NORRISTOWN, PENNSYLVANIA, A CORPORATION OF PENNSYLVANIA.

PATTERN WHEEL FOR KNITTING MACHINES.

Application filed February 2, 1921. Serial No. 441,879.

To all whom it may concern:

Be it known that I, KENNETH HOWIE, a citizen of the United States, and resident of Norristown, Pa., have invented certain new and useful Improvements in Pattern Wheels for Knitting Machines, of which the following is a specification.

My invention concerns pattern means for acting upon knitting instruments to control their actions to knit or tuck according to the pattern desired.

In the accompanying drawings,

Fig. 1 is an edge view of a trick wheel in connection with latch needles.

Fig. 2 is a view like Fig. 1 but looking from the opposite direction.

Fig. 3 is a plan view of the composite trick wheel.

The composite trick wheel consists of a lower disc or wheel 9 having an upstanding rim or flange 10, and a smaller diameter inner wheel or disc 11 arranged eccentrically to the lower member and having its upper surface in the same plane with the upper face of the upper edge of the flange or rim. In these faces shallow grooves or notches 12 are cut which are adapted to receive the butts 13 of the latch needles. These shallow notches are closed at their bottoms to afford supports for the needle butts and as the wheel is set in inclined position the needles will be lifted to knitting off position. The two discs are also provided with deep or clear-through notches or teeth 14 and when two of these notches align the butt of the needle will pass therethrough, in tucking position, as shown at B Fig. 1, and this needle will tuck.

The two wheels or discs have their peripheries coinciding at one point, or substantially so, because of their eccentric relation as at C.

A cam 15 is associated with the trick wheel which guards the needle in tucking position.

I claim:

1. In a knitting machine, knitting instruments, and a trick wheel composed of two discs, one having a flange with its edge

lying in the plane of the face of the other 50 wheel, said wheels being of different diameters, placed face to face and on displaced axes, said wheels having each shallow notches for knitting and other notches for tucking which notches act as drivers by 55 contact of their walls with the butts of the knitting instruments, said notches in each wheel being spaced according to the needle spacing to be driven thereby, substantially as described.

2. In combination in a knitting machine, knitting instruments, and a trick wheel arranged at an inclination, composed of two discs of different diameters arranged relatively off center and in substantially fixed 60 relation to each other and having notches to engage the knitting instruments to be driven thereby, some of said notches in each disc having closed bottoms to engage and lift the knitting instruments for knitting, and others of said notches being cut clear through the discs from the upper to the lower face to allow the butts of the instruments to pass therethrough in tucking position, each of 65 said wheels being turned by their notches 70 engaging the needle butts substantially as described.

3. In combination in a knitting machine, knitting instruments, and a trick wheel arranged at an inclination, composed of two 80 discs of different diameters arranged relatively off center and in substantially fixed relation to each other and having notches to engage the knitting instruments to be driven thereby, some of said notches in each disc 85 having closed bottoms to engage and lift the knitting instruments for knitting, and others of said notches being cut clear through the discs from the upper to the lower face to allow the butts of the instruments to pass 90 therethrough in tucking position, each of said wheels being turned by their notches 95 engaging the needle butts and cam means for acting on the needle butts in tucking position.

In testimony whereof, I affix my signature.

KENNETH HOWIE.
